ISAAC P. TICE, OF NEW YORK, N. Y., ASSIGNOR TO A. S. AND J. GEAR AND COMPANY, OF NEW HAVEN, CONNECTICUT.

Letters Patent No. 86,605, dated February 2, 1869.

IMPROVEMENT IN MOULDING-MACHINES.

The Schedule referred to in these Letters Patent and making part of the same.

To all whom it may concern:

Be it known that I, ISAAC P. TICE, of New York, in the county of New York, and State of New York, have invented a new Improvement in Wood-Moulding Machines; and I do hereby declare the following, when taken in connection with the accompanying drawings and the letters of reference marked thereon, to be a full, clear, and exact description of the same, and which said drawings constitute part of this specification, and represent, in—

Figure 1, a side view;

Figure 2, a side view of the cutter, and a portion of the arbor detached;

Figures 3 and 4, vertical central sections through the arbor, at right angles to each other; and in

Figure 5, a face view of the moulding cut upon the inclined table.

This invention relates to an improvement in wood-moulding machines, particularly applicable to the machine patented to Nathaniel Gear, November 8, 1853, and extended in 1867, the object being to improve the adjustment of the cutters and increase the facilities of the machine; and

The invention consists in constructing the collar between the two sets of cutters in two parts, the one screwed on to the other, so that the upper cutters may overlap to any desirable extent on to the lower cutters, and the elevation of the upper cutters be changed without necessarily changing the lower cutters.

To enable others to construct and use my improvement, I will fully describe the same as illustrated in the accompanying drawings.

A is the frame;

B, the table; and

C, the arbor or shaft, all constructed and arranged in the usual manner.

Upon the shaft is fixed or formed a lower head, D, to receive the lower edge of the lower cutters d, usually two in number.

a are the upper cutters, also usually two in number. Heretofore, between the two sets of cutters has been arranged a collar, in a single piece, fitted upon its under side to receive the upper edge of the lower cutters, and upon its upper surface, in like manner fitted to receive the lower edge of the upper cutters, a second head, E, being placed on to the shaft, so as to support the upper edge of the upper cutters, and confined, so as to hold all the cutters in place.

By this arrangement, it will be seen that the collar between the two cutters, being in one piece, renders impossible the adjustment of the upper and lower cutters relatively to each other, a serious difficulty in this class of machines, to overcome which, I form a collar, f, which fits closely to the shaft, and with a sleeve threaded so as to receive over it a second collar, h, the lower collar

f being fitted to receive the lower edge of the upper cutters a, as seen in fig. 4.

The upper collar h is in like manner fitted to receive the upper edge of the lower cutters d, as seen in fig. 3.

Therefore, by raising or lowering either of the two collars, h or f, the cutters supported thereby may be adjusted so that the lower edge of the upper set will overlap the upper edge of the lower set, as seen in fig. 2.

In the construction before described, for securing the cutters, it is necessary that the cutters be of an exact width, that is, the two cutters in each pair, for should one be a little wider than another, the upper head would bear upon the broader one first, and not be able to reach the second, or narrower.

To overcome this difficulty, I construct the upper head E concave upon the upper side, as in figs. 3 and 4, and bored out, so that while the upper side will fit closely to the arbor, the lower side of the hole will permit the head to tip in any direction.

Over this head I place a collar, F, its under surface formed to correspond to the upper surface of the head E. The one may be convex and the other concave, or vice versa.

Therefore, when the nut G is placed on to the arbor, so as to bear on the collar F, it will continue to force down the head until it bears alike on all the cutters. This forms, as it were, a universal adjustment of the cutters.

In working what are known as waved mouldings, that is, a surface having a corrugated form longitudinally, the material is moved by a pattern to and from the cutter, so as to produce the waved or corrugated surface.

To produce a still greater variety of surface, I arrange a table, H, hinged or secured to the frame at i, (or may be at the other end,) so that the unhinged end may be raised and set to any desired degree of elevation.

This inclination, combined with the usual means of guiding the material so as to produce the waved or corrugated surface aforesaid, gives to the moulding an appearance of being carved, as the cutters indicate the incline on the moulding; and this, combined with the waving cut, throws the cutters out, and starts again immediately under the point at which the cutters run out. The moulding thus has the appearance indicated in fig. 5.

Having fully described my invention,

What I claim as new and useful, and desire to secure by Letters Patent, is—

The combination of the two collars, f and h, with their respective cutters, substantially in the manner herein set forth.
